UNITED STATES PATENT OFFICE.

GEORGE A. BARNES, OF AKRON, OHIO, ASSIGNOR TO THE WHITMAN & BARNES MANUFACTURING COMPANY, OF SAME PLACE.

DESIGN FOR A GOLF-BALL.

SPECIFICATION forming part of Design No. 29,949, dated January 3, 1899.

Application filed November 17, 1898. Serial No. 696,733. Term of patent 14 years.

To all whom it may concern:

Be it known that I, GEORGE A. BARNES, a citizen of the United States, residing at Akron, in the county of Summit and State of Ohio, have by my own industry, genius, efforts, and expense invented and produced a new and original Design for Golf-Balls, of which the following is a specification, reference being had to the accompanying drawings, forming part thereof.

Assuming, for the purposes of the drawings, that $a d$ is a fixed horizontal axis through the center of the ball, then Figure 1 is a side view looking along said axis, and Fig. 2 is a front view taken on the line 2 of Fig. 1.

In the drawings, for the purposes of description, a represents one pole of the ball on the axis $a d$, and d the other pole; b , an equatorial circle of the ball cut by an imaginary plane $b b$ through its center perpendicular to $a d$; c , a circle on the surface of the ball cut by an imaginary plane $c c$ parallel to plane $b b$, passed through the ball at a point approximately three-fifths of the distance from the pole a to the center of the ball, and $c' c'$ a corresponding circle in the same relative position to the pole d .

Cut upon the surface of the ball are a series of diamond-shaped figures arranged as follows: Around the pole a are arranged five large diamond figures having an acute angle at a , their oblique angles lying in the imaginary circle c and their opposite acute angles in the imaginary circle c' . Around the pole

d are five other diamond figures having their oblique angles in circle c' and their opposite acute angles in circle c . The five diamonds about a mesh into those around d and form a lace-work of ten large diamond figures covering the surface of the ball, substantially as shown in the drawings. One of the ten diamond figures about pole d is shown as $defg$ and one about pole a as agh , Fig. 2, the line eg being common to both diamonds. Each of the large diamonds is subdivided by lines approximately parallel to its sides into a large number of small diamonds, substantially as shown.

The essential feature of my invention consists in the configuration produced by a golf-ball having several large diamond-shaped figures arranged around each principal pole, the diamonds around opposite poles meshing into each other and forming a lace-work of large diamond figures covering the entire ball, each of the large diamonds being subdivided into a large number of small diamonds with sides approximately parallel to the sides of the large diamonds, the whole presenting an ornamental and attractive appearance, as shown in the drawings.

What I claim is—

The design for a golf-ball herein shown and described.

GEORGE A. BARNES.
